UNITED STATES PATENT OFFICE.

JOSEPH CROWFOOT, OF BRIDGEPORT, CONNECTICUT.

MACHINE FOR MAKING COILED-WIRE FERRULES.

SPECIFICATION forming part of Letters Patent No. 291,496, dated January 8, 1884.

Application filed February 23, 1883. (No model.)

To all whom it may concern:

Be it known that I, JOSEPH CROWFOOT, of Bridgeport, in the county of Fairfield and State of Connecticut, have invented a new and 5 Improved Machine for Making Coiled-Wire Ferrules, of which the following is a full, clear, and exact description.

Reference is to be had to the accompanying drawings, forming a part of this specification, 10 in which similar letters of reference indicate corresponding parts in all the figures.

Figure 1 is a plan view of my improvement, parts being broken away. Fig. 2 is a side elevation of the same, partly in section. Fig. 15 3 is a side elevation of the polishing-brush and its driving-pulley and supporting bar. Fig. 4 is a sectional side elevation of the wire-guide and the jacket. Fig. 5 is a side elevation of the hollow split mandrel. Fig. 6 is a 20 side elevation of a part of a completed ferrule. Fig. 7 is a view in elevation, showing a part of the mandrel, its support, and gearing in the solder.

The object of this invention is to facilitate 25 the making of coiled-wire ferrules.

The invention consists in a machine for making coiled-wire ferrules constructed with a mandrel revolved by suitable mechanism within a stationary band having an inclined up- 30 per edge to raise the wire as it is coiled and form a space for the next coil.

The band and the lower part of the mandrel are surrounded by a jacket having apertures to admit solder, and a slot to receive the 35 wire to be coiled, and which serves as a guard to keep the coiled wire in place as it moves up the mandrel. The upper part of the mandrel is made tubular, and is slotted from its upper end, so that the said mandrel can be 40 kept cool more readily, and will allow the coiled wire to be moved upward upon it more easily. The machine is provided with a brush rotated from the driving mechanism of the mandrel for brushing the uncombined solder 45 from the coiled wire upon the upper part of the said mandrel and polishing the said wire, as will be hereinafter fully described.

A represents the frame of the machine, which is designed to be bolted to the sides of a vat, 50 B, containing molten or liquid solder, or to other suitable supports. The middle part of

the frame A is depressed, and to it is pivoted the lower end of the mandrel C, the upper part of which is made tubular, and is split from its upper end nearly to its lower end, 55 and is made of steel or other suitable elastic metal, to allow it to be compressed for convenience in slipping off the completed ferrule. If desired, the free upper ends of the strips of the mandrel C can be supported by a spring 60 to hold the said strips against the pull of the wire while being coiled. The mandrel C is supported in an erect position by a bearing, D, formed in a cross-plate of the frame A.

To the bearing-plate D is bolted the base- 65 flange of the jacket E, which has a number of perforations, F, formed in it to allow the solder to flow readily into the interior of the said jacket.

In one side of the jacket E is formed a slot, 70 G, extending downward from the upper end of the said jacket to receive the wire, H, to be coiled, and which is so formed as to be tangent to the side of the mandrel C, as shown in Fig. 1, so that the wire H will come in contact with the said mandrel in proper position to be coiled upon it. The interior of the jacket E is made so much larger than the mandrel C as to allow the coiled wire to slide freely up the said mandrel, and to adapt the said jacket 80 to serve as a guard to keep the said coiled wire in place while sliding up the mandrel.

In the lower part of the jacket E is placed a band, I, which is secured to the said jacket by a set-screw or other suitable means, in such a position that its upper edge will be about upon a level with the point at which the wire H comes in contact with the mandrel. The upper edge of the band I is inclined, the pitch of the inclination being such that the vertical shoulder joining the lowest and highest points of the said edge will have a length a little greater than the diameter of the wire to be coiled, and the direction of the inclination being such that the wire H will pass to the mandrel C across the vertical shoulder of the said edge, and come in contact with the mandrel below the last coil of the wire, the inclined edge of the band I pushing the wire upward as fast as it is coiled.

The machine is designed to be submerged in molten solder to such a depth that the en- 95 100

tering-point of the wire and the lowest two or three coils of wire upon the mandrel C will be beneath the surface of the solder. As the soldered coils of wire rise above the jacket E, 5 they are designed to be subjected to a blast of air from an ordinary fan-blower to cool the wire and allow the solder to harden quickly. The tubes of soldered coiled wire are made in pieces three feet (more or less) in length, and 10 are afterward cut into ferrules of the desired length.

To the lower end of the mandrel C is attached a gear-wheel, J, the teeth of which mesh into the teeth of a gear-wheel, K, attached to the 15 lower end of the vertical shaft L. The shaft L revolves in bearings in bars or arms attached to or formed upon the frame A, and to its upper part is attached a beveled-gear wheel, M, the teeth of which mesh into the teeth of the beveled-gear wheel N, attached to the inner end of the shaft O. The shaft O revolves in bearings formed upon or attached to the arm P, secured 20 to the frame A. To the outer end of the shaft O is attached a pulley, Q, to receive a driving-belt when the machine is to be driven by power, or a crank when the machine is to be operated by hand. As the tube of coiled wire passes to the upper part of the mandrel C, it 25 is wiped by a rotating brush, R, attached to the lower end of a short shaft, S, which revolves in bearings in a bar or arm, T, secured to the frame A.

To the upper end of the shaft S is attached a pulley, U, to receive an endless band, which 30 also passes around a pulley, V, attached to the upper end of the shaft L, so that the said brush will be driven from the driving mechanism of the machine.

The endless band is not shown in the drawings.

Having thus described my invention, I claim as new and desire to secure by Letters Patent—

1. The mandrel C of a machine for coiling

wire ferrules, made tubular and of elastic strips at the upper end, to admit of inward compression and a ready escape of the ferrule-tube, as described. 45

2. In a machine for coiling wire ferrules, the combination, with a rotary mandrel, of a fixed bearing, D, and a jacket, E, made fast to 50 said bearing, whereby the jacket will surround the coils of wire while the solder is being applied thereto, as described.

3. In a machine for making coiled-wire ferrules, the combination, with the rotary mandrel C and the stationary band I, having inclined upper edge, of the jacket E, having apertures F to admit solder, and an inclined slot, H, to receive the wire, substantially as herein shown and described, whereby the coiled 60 wire is kept in place as it is pushed up the mandrel, as set forth. 55

4. In a machine for making coiled-wire ferrules, the rotary mandrel C, made substantially as herein shown and described, with 65 its upper part tubular and slotted longitudinally from its upper end, whereby the mandrel can be kept cool more readily, and will allow the coiled wire to move upward upon it more easily, as set forth. 70

5. In a machine for making coiled-wire ferrules, the combination, with the rotary mandrel C and its driving mechanism, of the rotary brush R and its driving mechanism, substantially as herein shown and described, 75 whereby the uncombined solder is brushed off and the coiled wire is polished, as set forth.

6. In a machine for coiling wire ferrules, the combination, with the mandrel C, bearing D, and jacket E, of a stationary band, I, inclined at the upper edge to push the wire upwardly as fast as coiled, as described. 80

JOSEPH CROWFOOT.
